UNITED STATES PATENT OFFICE

CARL W. HOLLINGSWORTH, OF MARSHALLTOWN, IOWA

BREATHER CAP FOR CRANK CASINGS

Application filed April 5, 1930. Serial No. 441,984.

This invention relates to internal combustion engines, and more particularly to the breather cap that closes the inlet pipe through which oil is poured, to fill the crank casing.

6 The primary object of the invention is to provide a breather cap having an internal baffle so constructed that oil will be trapped and returned to the crank casing, eliminating any possibility of the air passing into and out 10 of the crank casing, blowing the oil to cause a leakage.

Another object of the invention is to provide a breather cap of this character which may be constructed at comparatively small 15 cost, due consideration being given to the strength and durability of the device.

A further object of the invention is to provide a breather cap which may be readily 20 and easily inserted in the open end of a crank casing filling pipe, eliminating the necessity of making changes in the construction to install the device.

With the foregoing and other objects in view, which will appear as the description 25 proceeds, the invention resides in the combination and arrangements of parts and in the details of construction hereinafter described and claimed, it being understood that changes in the precise embodiment of the invention herein disclosed, may be made within 30 the scope of what is claimed without departing from the spirit of the invention.

Referring to the drawing:

Figure 1 illustrates a vertical sectional view through a breather cap constructed in accordance with the invention.

Figure 2 is a transverse sectional view taken on line 2-2 of Figure 1.

Referring to the drawing in detail, the 40 breather cap includes a body portion comprising a straight rim 5 and a tapered lower portion indicated by the reference character 5¹, the same being substantially funnel shaped.

45 The lower end of the body portion is formed with a depending straight wall 6 so that the device may be readily positioned in a filling opening or pipe, to take the place of the usual cover now employed.

50 A slot 7 is formed in the lower portion of

the device and lends resiliency to the device so that the device will be securely held in position by frictional contact with the pipe or opening in which the extension 6 is positioned.

Extending upwardly from the rim 5 of the body portion, are arms 8 that are arranged in spaced relation with respect to each other, the arms being provided with tapered or reduced extremities 9, see at the right of Figure 1, that pass through slot 9¹ in the cap 10, where they are bent over the cap to secure the cap to the body portion. Due to the construction of the arms 8, it will be seen that the cap is supported in spaced relation with the upper edge of the body portion to allow a free passage of air into and out of the body portion, under the cap.

The lower edge of the cap extends downwardly and terminates at a point below the upper edge of the rim 5 of the body portion, guarding the open end of the body portion against the entrance of foreign matter from entering the crank casing through the body portion.

Positioned within the cap, and secured thereto by means of the bolt 11, is a central inverted cap-shaped member 12, formed with downwardly and outwardly extended spaced fingers or baffles 13, which are of sufficient length to approach and preferably engage the shoulder 14 formed on the body portion 5, to direct the oil collected on the fingers to the inclined wall of the body portion. These fingers 13 are spaced apart in such a way that sufficient spaces are formed between them to permit the passage of air to and from the crank casing, and are attenuated or pointed at the ends.

From the foregoing, it will be seen that due to the construction shown and described, oil which will be thrown or splashed within the crank casing, and which would automatically be forced from the crank casing by the motor breathing, will be splashed against the inverted cup-shaped member 12 and collected by the fingers 13, from where it will be returned to the crank casing, by flowing down the inclined wall of the body portion.

I will now explain a little more fully the

operation of my breather cap. The crank cases of automobiles are provided with outlets or breather tubes. The reason for this is that some compressed gases escape past the pistons into the crank case and a pressure tends to be built up in the crank case unless some suitable outlet is provided.

In instances where the breather tube has been closed up, it has been found that the pressure forces the gases out at the rear of the crank case assembly and that oil is likewise forced out so that there is a very rapid loss of oil in the crank case.

Even where the breather tube is provided, it becomes important to provide a breather cap which will prevent the passage of fine oil mist out of the crank case with the air passing through the breather tube.

Where a cap like mine is provided, nearly all of the fine particles of oil carried upwardly with the moving current of air are saved. The air and oil impinge upon the under face of the baffle device and upon the inner surfaces of the fingers 13. Generally speaking, the oil is deposited in such fine particles that it will adhere to the metal, but will not flow downwardly until additional oil is deposited. The oil tends to adhere to and flow down the wall of the inverted cup-shaped member 12 and directed to the fingers 13 and to the interior wall of the body 5 of the breather cap, rather than to drop straight down the passage through the outgoing air current forced through the breather.

For accomplishing this saving of the oil, the provision of the outwardly inclined baffle fingers is of importance as affording a means along which the oil may conveniently travel. These fingers are made preferably to contact with the inner face of the body portion 5 because the oil then travels more freely from the fingers to the wall of the body portion 5. The attenuated shape of the lower ends of the fingers also contributes to this desirable result.

Another feature of the present structure which is of importance for saving oil is the arrangement of the breather cap with the enlarged portion of the body 5 at its upper end of the restricted straight wall portion 6. Because of the provision of this enlarged portion, there is provided a dead air space in which the oil can collect on the metal outside of the path of the pressure and from which it will not be blown back by the pressure passing through the breather cap. If the breather body were of the same diameter for its entire length from top to bottom the passing current of air would prevent the down-flow of oil on the inner surface of the body and blow out a considerable portion of it to atmosphere. In the dead air space, the oil accumulates into large enough film-like quantities to flow down the portion 6 without again being blown out or carried out by

the outwardly moving air current. The oil adheres to the wall of the portion 5¹ and travels around the shoulder at the lower end thereof and forms a film around the inner wall of the reduced neck of the body of the cap. Thus I have provided a breather cap, of such construction as to allow free outflow of air, so that no pressure is built up in the crank case. Other caps are provided with baffles to catch the oil, but which obstruct the free passage of air. But I have provided a structure with a storage or dead air space outside of the main path of air travel through the cap, in which oil can accumulate.

What I claim is:

1. A breather cap comprising a body portion open at its ends, a cap section supported above the body portion and an inverted cup-shaped baffle device secured to the cap section and having a plurality of spaced fingers extending downwardly and outwardly within the cap section and having their ends arranged in close proximity to the inner surface of the body portion for causing oil to flow back to the crank casing.

2. A breather cap comprising a body portion open at its ends, a cap section supported above the body portion, and an inverted cup-shaped baffle device, secured to the under side of the cap section, having a plurality of spaced fingers extending downwardly and outwardly within the cap section and having their ends pointed and arranged in close proximity to the inner surface of the body portion for causing oil to flow back to the crank casing.

3. A breather cap comprising a body portion open at its ends, a cap section supported above the body portion, and a baffle device having a central member fixed to the inner surface of said cap section and also having a plurality of spaced fingers formed on and radiating from said central member, said fingers extending downwardly and outwardly within the cap section and having their ends contacting the inner surface of the body portion for causing oil to flow back toward the crank casing.

4. A breather cap comprising a body portion open at its ends, a cap section supported above the body portion and a baffle device having a central member fixed to the inner surface of said cap section and also having a plurality of spaced fingers formed on and radiating from said central member, said fingers extending downwardly and outwardly within the cap section and having their ends pointed and contacting the inner surface of the body portion for causing oil to flow back to the crank casing.

5. In a breather cap a lower cylindrical portion adapted to be supported by a breather tube, a portion thereabove of greater diameter than said first portion, a cap spaced substantially above said second portion having a

down-turned peripheral flange of greater diameter than and overlapping the upper end of said second portion, an inverted cup-shaped baffle member fixed in the upper interior of said cap comprising a down-turned flange with downwardly and outwardly inclined fingers projecting therefrom and terminating in close proximity to the wall of the second portion of the body with greater diameter.

6. In a breather cap, a body portion having a cylindrical portion adapted to be supported by a breather tube, a portion communicating therewith and of gradually increasing diameter toward its upper end and affording an inclined wall, a cap spaced above said second portion having a down-turned peripheral flange of greater diameter than and overlapping the upper end of said second portion, an inverted cup-shaped baffle member fixed in the upper interior of said cap and comprising a down-turned flange provided with downwardly and outwardly inclined fingers, having their ends terminating in close proximity to the inclined wall of the second mentioned body portion.

In testimony that I claim the foregoing as my own, I have hereto affixed my signature.

CARL W. HOLLINGSWORTH.
